RAYMOND D. VERCLER, OF LOS ANGELES, CALIFORNIA.

JEWELER'S TESTING-CASE.

1,263,629.

Specification of Letters Patent. Patented Apr. 23, 1918.

Application filed July 18, 1917. Serial No. 181,396.

To all whom it may concern:

Be it known that I, RAYMOND D. VERCLER, a citizen of the United States, residing at Los Angeles, in the county of Los Angeles and State of California, have invented certain new and useful Improvements in Jewelers' Testing-Cases, of which the following is a specification.

The invention relates to an acid bottle container, and particularly to the class of jewelers' acid testing cases.

The primary object of the invention is the provision of a case of this character, wherein in bottles containing acids for testing purposes are conveniently held to be readily accessible, the case being devoid of metal hinges and catches to eliminate any action of the acid fumes thereon, while in addition to the bottle compartments, other compartments are arranged within the case for the reception of testing slabs or stones, and testing needles, which are freely accessible and yet not subject to attack by acid fumes, thereby preventing corrosion and sweating of the needles.

Another object of the invention is the provision of a case of this character wherein the same, when open, affords a testing table which will absorb any acid should the same spill from the testing stone or slab, thereby eliminating the dropping of the acid on a show-case or other support, and causing damage to the clothes of a user.

A further object of the invention is the provision of a case of this character wherein, on the opening thereof, it will have a firm base to prevent the turning or tipping over of the same, which would be more or less dangerous, in view of the use to which the case is put.

There are various other objects and advantages of this invention besides the above, all of which will be hereinafter more particularly brought out in the following specific description in the preferred embodiment of the invention, the same being illustrated in the accompanying drawing, wherein:

Figure 1 is a perspective view of a case constructed in accordance with the invention, closed.

Fig. 2 is a similar view with the case open and its lid forming the testing table or bed.

Fig. 3 is a vertical longitudinal sectional element shown by full lines the case open, and by dotted lines the case closed.

Similar reference characters indicate corresponding parts throughout the several views in the drawing.

In constructing a practical embodiment of the invention in accordance with the illustrated example, the case A is provided, preferably comprising a substantially rectangularly shaped box-like body 10, made from wood, although the same may be made from any other material, open at its top and having interiorly thereof in proximity to one end a transverse partition 11, which is fastened to opposite side walls of said body in any suitable manner, and divides the latter into independent compartments 12 and 13, respectively. The compartment 12 is designed to receive bottles 14 containing acids used by jewelers for testing purposes, while the compartment 13 is adapted to receive a testing slab or stone and testing needles, not shown, of the usual construction.

The partition 11 is of less height than the walls of the body 10 with the exception of one end wall 15 thereof which is of similar height thereto, and in this manner a clearance is afforded for a swinging lid B hereinafter fully described.

The lid B comprises a board-like section 16 which constitutes a testing table when the lid has been completely swung to open position, the section being swingingly supported on a pivot rod 17 passed through the same near one end edge, and journaled in the opposing sides of the body 10 above the end wall 15 for the swinging of said section to open or closed positions, and on the closing of the same, as illustrated by dotted lines in Fig. 3 of the drawing, it fits within the body and rests upon the partition 11 with the outer surface of said section flush with the upper edges of said body, thereby completely closing the compartment 13 therewith.

The free end of the section 16 has fastened thereto, or integral therewith, a crowning cap 18 which constitutes a cover for the compartment 12 receiving the bottles 14 to completely house the same and accommodate the heights of such bottles placed therein, the cap 18, when the lid is opened, being designed to form a leg for the section 16 to hold it substantially horizontal and level for the convenient use thereof at its upper surface as a work table or bed, and for the testing stone or slab which is placed thereon for use with the testing

needles by jewelers. The interior of the cap 18, when the lid is open, can be used as a compartment 19 for receiving jewelers' tools, or any other article, while the jeweler 5 is at work testing.

In the use of the case, should any acid spill from the stone or slab upon the testing table constituted by the section 16 when the lid is open, it will be absorbed by the 10 wood or other material forming the section and, in this manner, be prevented from dropping upon the support for the case and causing damage to the clothes or danger to the jeweler.

15 The lid B, when closed, will completely cover the body 10 and the latter will not easily tip over or cause the spilling of the acids which, if strong, will be more or less dangerous.

20 The end wall 20, opposite the wall 15, is strengthened by an inner wall 21 so that this end is a double wall to reinforce said body 10 at this point.

From the foregoing it is thought that the 25 construction and the manner of use of the case will be clearly understood and, therefore, a more extended description has been omitted.

It is to be understood that changes, variations and modifications may be made, such as come properly within the scope of the 30 appended claims, without departing from the spirit of the invention or sacrificing any of its advantages.

35 What is claimed is:—

1. A case of the character described, comprising a body having a transverse partition therein to form independent compartments, one of which is adapted to receive bottles, 40 and a lid having a board-like section for closing one compartment and also having a crowning cap to cover the bottles of the other compartment, said section and cap moving as a rigid unit, and the cap, when the lid is moved back, serving as a support therefor, and enabling the board-like section of the lid to be used as a table.

45 2. A case of the character described, comprising a body having a transverse partition 50 therein to form independent compartments,

a lid having a board-like section for closing one compartment and also having a crowning cap for the other compartment, said cap being open at one side, which open side receives the necks of bottles placed in said 55 compartment, and a pivot swingingly connecting the lid to the end of the body, whereby when the lid is swung outwardly from the body, the cap is inverted with the open side uppermost so as to form a receptacle, while the rest of the lid forms a table with the cap serving as a support therefor.

60 3. A case of the character described, comprising a body having a transverse partition therein to form independent compartments, 65 a lid having a board-like section for closing one compartment and also having a crowning cap for the other compartment, and a pivot swingingly connecting the lid to the end of the body, the cap when the lid is open 70 and swung back from the body being designed to form a supporting leg for the board-like section, said section being capable of use as a table.

4. A case of the character described, comprising a body having a transverse partition therein to form independent compartments, one end wall of the body and the partition being of uniform height with respect to each other, but of less height than 80 the remaining walls of the body, a lid having a board-like section for closing one compartment and also having a crowning cap for closing the other compartment, a pivot swingingly connecting the lid to the end 85 of the body, the crowning cap when the lid is open and swung back from the body being designed to form a supporting leg for the board-like section, which section serves as a table and on closing the said lid 90 the section will fit within the body above the shorter end wall and said partition to have the outer surface of the section flush with the top edges of the body.

In testimony whereof I affix my signature in the presence of two witnesses.

RAYMOND D. VERCLER.
